FIG.4.

FIG.5.

FIG.6.

FIG.7.

FIG.8.

Fig. 1 is a side elevation of a boarding ladder for boats or the like showing our new design, with the ladder in extended position.

Fig. 2 is a rear elevation thereof.

Fig. 3 is a side elevation thereof similar to Fig. 1 showing the ladder in folded position.

Fig. 4 is a top plan view thereof taken substantially from the line 4—4 of Fig. 1.

Fig. 5 is a view of the under side of the boarding ladder as shown in Fig. 1.

Fig. 6 is a front elevation of the boarding ladder.

Fig. 7 is a longitudinal sectional view of the boarding ladder taken along the line 7—7 of Fig. 4.

Fig. 8 is a transverse section through the boarding ladder taken along the line 8—8 of Fig. 7, looking in the direction of the arrows.

The fragmentary portions of a boat and the clip shown in broken lines are included for illustrative purposes only.

We claim:

The ornamental design of a boarding ladder for boats or the like, substantially as shown and described.
